CLAIM

The ornamental design for a display panel or portion thereof with a transitional mixed reality graphical user interface, as shown and described.

DESCRIPTION

FIG. 1 is a front view of a display panel or portion thereof with a transitional mixed reality graphical user interface showing a first image in a sequence of a first embodiment of our design;

FIG. 2 is a front view of a second image thereof;

FIG. 3 is a front view of a third image thereof;

FIG. 4 is a front view of a fourth image thereof;

FIG. 5 is a front view of a display panel or portion thereof with a transitional mixed reality graphical user interface showing a first image in the sequence of a second embodiment of our design;

FIG. 6 is a front view of a second image thereof;

FIG. 7 is a front view of a third image thereof; and,

FIG. 8 is a front view of a fourth image thereof.

The appearance of the image sequentially transitions between the images shown in FIGS. 1 through 4 and FIGS. 5 through 8. The process or period in which one image transitions to another forms no part of the claimed design. The outermost broken line rectangle illustrates a display panel or portion thereof that forms no part of the claimed design. The remaining broken lines illustrate portions of a graphical user interface or a mixed reality environment, and form no part of the claimed design.
